APPARATUS FOR UNLOADING WHEELED VEHICLES OF THE BOTTOM-DISCHARGE TYPE

Herbert Frederick Henry Shields,
London, EnglandApplication June 10, 1943, Serial No. 490,340
In Great Britain April 21, 1942

2 Claims. (Cl. 214—44)

This invention relates to methods of and apparatus for unloading wheeled vehicles of the bottom-discharge type, such as railway wagons, containing fragmentary materials of various kinds, such as coal, gravel and the like, herein-after referred to generally as "coal," and loading the same.

In coal-stocking and reclaiming plants used heretofore, the coal wagons have run to and from a wagon tippler on one pair of rails of a railway track, and a travelling loader of the drag scraper type for filling empty wagons has been arranged to run on an adjacent pair of rails to prevent the loader from interfering with the running of the loaded and empty coal wagons on their track.

An important object of the present invention is to obviate the necessity of providing two distinct tracks, one for a tippler or other unloading means, and a second for the loader, and to arrange the loader and unloading means in an improved manner.

Another object of the invention is to provide an improved construction of apparatus which shall enable wheeled vehicles of the bottom-discharge type to be unloaded in an improved manner.

According to an important feature of the invention there is provided apparatus for unloading wheeled vehicles of the bottom-discharge type, comprising in combination a main frame that is arranged to travel along a ground track, an upper track that has end portions constituting ramps that slope downwards to rails on the ground track, which upper track has a middle portion carried by the cage for supporting a loaded wheeled vehicle therein, lifting means that is mounted on the main frame and is arranged to lift the cage with the loaded vehicle therein bodily and place it at a situation vertically above a position at the side of the ground track, at which a pile of fragmentary material is to be formed by emptying the loaded vehicle, which lifting means comprises a runway that extends outboard upwards from a situation vertically above the middle portion of the upper track, a pulley on the outer end of the runway, and suspension means for carrying the cage arranged to travel along the runway, and power-driven means that is arranged to operate the lifting means and comprises a winch supported on the main frame, and a rope that passes around said pulley and has one end attached to the winch and its other end operatively connected to the suspension means.

One embodiment of the invention is diagrammatically illustrated by way of example in the accompanying drawings, wherein:

Figure 1 is an end elevation showing one form of apparatus according to the invention

for unloading and loading wheeled vehicles of the bottom-discharge type, and

Figure 2 is a plan view thereof.

Like reference characters designate like parts in both views.

Referring to the drawings, apparatus for unloading railway wagons of the bottom-discharge type comprises a gantry-like main frame, designated generally 10, of arched construction.

10 This frame 10 is rectangular as viewed in plan and in end elevation, and has front and rear longitudinal sides 14 and 16, respectively, and two ends 18, 20. The frame is carried by two bogies 19 and 21 having wheels 22 and 24, respectively, arranged to run on rails 26 on sleepers 27 of a ground track, on which empty and loaded railway wagons can run to, through and from the frame as described hereinafter. Leveling and load-distributing means in the form of hydraulic or manually operated jacks 29 may be provided at the ends of the frame, and/or if desired along one or both sides thereof, for distributing the load when working and for leveling the main frame.

25 The frame 10 is provided with a short upper track having two sloping end portions 30, 32 constituting ramps, and a horizontal middle portion 34, 36. This middle portion has between its ends 34 a detachable central portion 36, as described hereinafter, the end portions 34 being supported by transverse frame members 35. The two ramps are hinged or pivoted respectively at 38 and 40 to the outer ends of the middle portion of the upper track, preferably so as to swing about horizontal and vertical axes, and they slope downwards to the rails 26 of the ground track. This upper track is the same gauge as the rails 26 and lies above and travels on the ground track when the frame 10 is moved 40 along the latter.

Unloading means for a bottom-discharge wagon 42 having wheels 44 on the upper track comprises a rectangular portable cage 46, whereof the bottom 48 carries the central part 36 of the upper track. The top 50 of the cage has at its ends suspension means comprising two hangers 52, 54 respectively equipped with pulleys 56, 58 arranged to run respectively on two beams 60, 62 of an inclined runway that extends from the framework 10 outwards and upwards from a situation above the wagon 42 on the upper track to a situation vertically above a position at the side of the ground track 26, at which a pile of coal 64 is to be formed by emptying a loaded wagon. These beams 60, 62 are supported respectively by lattice-girder structures 61, 63 tied together by bracing 65.

Hauling means for the cage 46 comprises a winch having two haulage drums 66, 68 that can be driven in the same direction by an elec-

tric motor 70 through reduction gearing 72 and a shaft 74 operatively connected to the drums, which hauling means is housed in a cabin 75 at the rear of the frame 10. Two ropes 76, 78 are attached respectively at one end to the drums 60, 68, and are led therefrom respectively over guide pulleys 80, 82 near the top of the framework 10, round pulleys 84, 86, respectively, on the outer ends of the beams 60, 62 respectively, of the runway, and have their other ends attached to the hangers 52, 54, respectively. This hauling means enables a loaded wagon resting on the rails 32 in the cage 46 to be moved to its outer position shown in broken lines in Figure 1, in which position by opening bottom doors of the wagon the coal can be discharged to form the pile 64, which can be stocked-out by a drag scraper bucket, not shown. The bottom of the cage preferably also carries a deflecting plate or chute 88 extending from end to end thereof and arranged to deflect the falling coal away from the frame 10. After a wagon has been emptied and the cage has been returned to the middle of the framework, the empty wagon can be run off the upper track, down one of the sloping ramps 30, 32, and onto the ground track 26. As described so far, the apparatus, constituting an unloader, is adapted for unloading vehicles of the bottom-discharge type, and does not obstruct the transit of either empty or loaded wagons on the ground track.

When the apparatus described above is to be used also for loading such vehicles, the main frame 10 may be provided with loading means of the drag scraper type comprising a coal ramp 90 that has an outlet 91 and is mounted on the main frame above the upper track to swing about a horizontal axis at 92, and a scraper bucket, not shown, attached at the front and rear to a drag line hauled by power-operated means on the main frame.

It will be appreciated that when the apparatus is provided with such loading means of the drag scraper type, empty wagons to be loaded can be run successively on to the upper track in the apparatus for receiving coal from the loading ramp 90, and after being loaded with the coal ramp 90 in its lower position shown in broken lines, can then run on to the ground track at the opposite end of the framework, while loaded wagons to be emptied can run successively on to the upper track and into the cage, and after being unloaded at one side of the ground track, the empty wagons can be returned on to the upper track within the main frame and run down on to the ground track. The apparatus, which then forms a combined loader and unloader, also forms no obstruction to the transit of either empty or full wagons on the ground track. To permit the coal ramp 90 to swing down to its lowest position indicated in broken lines, the front longitudinal member at the top of the cage 46 is cranked, as indicated at 94 in Figure 1.

The invention thus provides for stocking-out coal from loaded vehicles by means of apparatus of the drag scraper type arranged to run on a ground track, by successively running loaded bottom-discharge vehicles along rails of the ground track to a predetermined unloading position, preferably situated at an elevation above the ground, at the apparatus, removing coal

from the vehicles by moving the vehicles bodily to a situation at one side of the track to form at the side of the track a heap of material, stocking-out the heap by a drag scraper to form a dump, and returning the empty vehicles to the predetermined position on or above the ground track, and running the empty vehicles along said rails away from the unloading position.

10 I claim:

1. Apparatus for unloading wheeled vehicles of the bottom-discharge type, comprising in combination a main frame that is arranged to travel along a ground track, a portable cage situated thereon above the ground track, an upper track that has end portions constituting ramps that slope downwards to rails on the ground track, which upper track has a middle portion carried by the cage for supporting a loaded wheeled vehicle therein, lifting means that is mounted on the main frame and is arranged to lift the cage with the loaded vehicle therein bodily and place it at a situation vertically above a position at the side of the ground track, at which a pile of fragmentary material is to be formed by emptying the loaded vehicle, which lifting means comprises a runway that extends outboard upwards from a situation vertically above the middle portion of the upper track, a pulley on the outer end of the runway, and suspension means for carrying the cage arranged to travel along the runway, and power-driven means that is arranged to operate the lifting means and comprises a winch supported on the main frame, and a rope that passes around said pulley and has one end attached to the winch and its other end operatively connected to the suspension means.

2. Apparatus for unloading wheeled vehicles of the bottom-discharge type, comprising in combination a main frame that is arranged to travel along a ground track, a portable cage situated thereon above the ground track, an upper track that has end portions constituting ramps that slope downwards to rails on the ground track, which upper track has a middle portion carried by the cage for supporting a loaded wheeled vehicle therein, lifting means that is mounted on the main frame and is arranged to lift the cage with the loaded vehicle therein bodily and place it at a situation vertically above a position at the side of the ground track, at which a pile of fragmentary material is to be formed by emptying the loaded vehicle, which lifting means comprises a runway that extends outward upwards from a situation above the middle portion of the upper track, and comprises two beams arranged in spaced parallel relation, two pulleys mounted one on the outer end of each beam, and suspension means comprising two hangers arranged each to run along one of the beams and to support the cage therefrom, and power-driven means that is arranged to operate the lifting means and comprises a winch having two rope drums supported on the main frame, and two ropes one allotted to each rope drum, each of which ropes passes round one of said pulleys and has one end attached to its allotted winch, and the other end operatively connected to the suspension means.

70 HERBERT FREDERICK
HENRY SHIELDS.
